DESIGN FOR A COMBINATION PIN AND WATCH OR SIMILAR ARTICLE

Abraham Fingerhut, New York, N. Y.

Application April 3, 1941, Serial No. 100,107

Term of patent 3½ years

To all whom it may concern:

Be it known that I, Abraham Fingerhut, a citizen of the United States and residing in Manhattan, in the city, county, and State of New York, have invented a new, original, and ornamental Design for a Combination Pin and Watch or Similar Article, of which the following is a specification, reference being had to the accompanying drawing, forming part thereof, wherein

Fig. 1 is a front elevational view of a combination pin and watch showing my new design.

Fig. 2 is a view similar to Fig. 1 showing the watch element turned 90° from the position shown in Fig. 1.

Fig. 3 is a side view of Fig. 1.

I claim:

The ornamental design for a combination pin and watch or similar article, substantially as shown.

ABRAHAM FINGERHUT.
